M. DYSTHE

CHECK STUB HOLDER

Filed Jan. 18, 1924

Patented Apr. 7, 1925.

1,532,389

UNITED STATES PATENT OFFICE.

MARTINIUS DYSTHE, OF MINNEAPOLIS, MINNESOTA.

CHECK STUB HOLDER.

Application filed January 18, 1924. Serial No. 696,999.

To all whom it may concern:

Be it known that I, MARTINIUS DYSTHE, a citizen of the United States, residing at Minneapolis, in the county of Hennepin and 5 State of Minnesota, have invented certain new and useful Improvements in Check Stub Holders; and I do hereby declare the following to be a full, clear, and exact description of the invention, such as will enable others skilled in the art to which it 10 appertains to make and use the same.

My invention has for its object to provide an extremely simple, inexpensive and highly efficient device for holding the stubs of 15 check books out of the way so as to expose the stub or stubs of a check or checks to be made out, and also for holding any check or checks which may have been made out but not detached from their stubs.

20 To the above end, the invention consists of the novel devices and combinations of devices hereinafter described and defined in the claims.

25 In the accompanying drawings, which illustrate the invention, like characters indicate like parts throughout the several views.

Referring to the drawings:

Fig. 1 is a perspective view of a partly 30 open check book having the improved stub holder attached to one of the covers thereof and positioned to hold the stubs when the check book is partly open.

Fig. 2 is a fragmentary view corresponding to Fig. 1 with the exception that the 35 check book is completely open;

Fig. 3 is a perspective view of the shift- 40 able anchor and attached end portion of the ribbon;

Fig. 4 is a detail view principally in section taken on the line 4—4 of Fig. 2, on an enlarged scale; and

Fig. 5 is a perspective view of the permanent anchor.

45 The numeral 6 indicates the cover of a check book, within which is bound stubs 7 having attached checks 8 which may be separated therefrom, and from each other on the perforated lines 9. As shown, there are 50 three checks to the page, but, of course, the holder will work equally as well whether there is one or more checks to the page.

55 The improved check stub holder comprises a permanent anchor 10, a shiftable anchor 11 and a ribbon 12 connecting said shiftable anchor to the permanent anchor. The per-

manent anchor 10 has at its ends outturned feet 14 which rest on the inside of the front cover 6 and support said anchor with clearance thereunder to receive the ribbon 12. 60 This permanent anchor 10 is detachably secured to the cover 6 near its free end portion by split fasteners 15, but in some instances it might be desirable to permanently secure the same thereto by rivets. 65

A longitudinal slot 16 is formed in the permanent anchor 10 to receive the ribbon 12. This ribbon 12 is secured to the permanent anchor 10 with freedom for longitudinal sliding adjustment to vary the operative 70 length thereof and is laced under and over said anchor and through the slot 16, as best shown in Fig. 4. The shiftable anchor 11 is in the form of a flat plate having at one edge a long slot 17 through which the respective end of the ribbon 12 is looped and secured by stitches. This shiftable anchor 11 is adapted to be inserted between the bound edges of the stubs 7, and at which time the front cover 6 is held only partly so 75 open to put slack in the ribbon 12, as shown in Fig. 1.

When the front cover 6 is completely open the ribbon 12 is drawn taut and thereby securely holds the stubs 7 and attached 80 checks 8, which may be between the shiftable anchor 11 and the front cover 6. It will be noted that the length of the ribbon 12 is such that the checks 8 may be folded thereunder between the attached stubs and the 85 permanent anchor 10. To vary the operative length of the ribbon 12 it is only necessary to turn said ribbon outward in respect to the front cover 6, and draw either end thereof to slide the ribbon 12 on the permanent anchor 10. 90

95 From the above description and by reference to the drawings it will be noted that the stubs and checks will be securely held on the front cover 6 so that they are entirely 100 out of the way, thus leaving the checks and stubs to be filled out fully exposed. The shiftable anchor 11 may be very quickly and easily removed from between the bound edges of the stubs, and another leaf of stubs 105 turned under the ribbon together with any checks which may be attached thereto, and said anchor again inserted between the bound edges of the stubs.

110 The improved check stub holders may be furnished with each check book or they may be sold separately and attached to a check

book cover by the purchaser. The ribbon 12 or shiftable anchor 11, or both, may be used for advertising purposes.

The term "check book" is herein used in a broad sense to cover various different kinds of books, such as stock books and the like.

What I claim is:

1. A check stub holder comprising a permanent anchor attachable to the cover of a check book, a shiftable anchor adapted to be inserted between check stubs at their bound edges, and a ribbon connecting the shiftable anchor to the permanent anchor.
2. A check stub holder comprising a permanent anchor attachable to the cover of a check book, a shiftable anchor adapted to be inserted between check stubs at their bound edges, and a ribbon connecting the shiftable anchor to the permanent anchor, said ribbon being adjustable in respect to one of said anchors to vary its operative length.
3. A check stub holder comprising a permanent anchor attachable to the cover of a check book, a shiftable anchor adapted to be inserted between check stubs at their bound edges, and a ribbon connecting the shiftable

anchor to the permanent anchor, said shiftable anchor being in the form of a flat plate.

4. A check stub holder comprising a permanent anchor attachable to the cover of a check book, a shiftable anchor adapted to be inserted between check stubs at their bound edges, and a ribbon connecting the shiftable anchor to the permanent anchor, said ribbon being of such length as to hold thereunder between the two anchors, check stubs and attached checks.

5. A check stub holder comprising a permanent anchor attachable to the cover of a check book, a shiftable anchor adapted to be inserted between check stubs at their bound edges, and a ribbon connecting the shiftable anchor to the permanent anchor, said permanent anchor having a transverse slot, said ribbon being laced around the permanent anchor and through the slot therein to adjustably connect said ribbon thereto.

6. The structure defined in claim 1, in which the permanent anchor may be detachably secured to the cover of a check book.

In testimony whereof I affix my signature:

MARTINIUS DYSTHE.
